UNITED STATES PATENT OFFICE.

JOHN A. MOSHER, OF CHICAGO, ILLINOIS, ASSIGNOR TO THE ADAMS & WESTLAKE COMPANY, OF SAME PLACE.

ACETYLENE-GAS-GENERATING LAMP.

SPECIFICATION forming part of Letters Patent No. 633,656, dated September 26, 1899.

Application filed November 21, 1898. Serial No. 697,072. (No model.)

To all whom it may concern:

Be it known that I, JOHN A. MOSHER, a citizen of the United States of America, and a resident of Chicago, county of Cook, and State of Illinois, have invented certain new and useful Improvements in Acetylene-Lamps, of which the following is a full, clear, and exact description, and which are illustrated in the accompanying drawings, forming a part thereof.

10 It is found in practice that in that type of acetylene-lamps in which the generator is combined with the lamp the parts become so highly heated from the chemical action that the gas is delivered to the burner-tip at a 15 very high temperature, and in consequence it burns with a far less luminous flame than when cool. This is understood to be due in part to the fact that when heated it clogs the burner-tip very rapidly and also that it carries out of the generating-chamber a very considerable percentage of steam.

The object of my invention is to overcome this difficulty by providing means for cooling the gas after it leaves the generating-chamber and before it reaches the burner-tip, so that whatever moisture it may be loaded with will be condensed and the temperature will be so low that the tendency to clog the tip will be greatly reduced. I accomplish this 30 object by providing a cooling and condensing chamber intermediate of the generator and the flame-chamber and which has a very extended case, and preferably this chamber is formed around the water-chamber, so that 35 the gas passes over surfaces one of which is water-cooled and the other of which is exposed to the cooling influence of the atmosphere.

The invention is fully illustrated in the accompanying drawings, in which—

Figure 1 is a vertical central section of a bicycle-lamp embodying it. Fig. 2 is a plan section on the line 2 2 of Fig. 1, and Fig. 3 is a plan section on the line 3 3 of Fig. 1.

45 While I show in the drawings a bicycle-lamp which exemplifies my invention, it is obvious that it may be applied as well to house or other lamps, especially those which contain their own generators.

50 The lamp shown is provided with a flame-

chamber A of any preferred form and a burner B, which also forms no part of the invention. It has a water-chamber C, which, as shown, is directly below the flame-chamber, and a generating-chamber D at the bottom of the lamp-body. At d is shown the water-passage connecting the water-chamber with the generating-chamber, and at e a valve for controlling this passage.

The water-chamber is made with two side 60 and bottom walls E F, which are spaced apart to form therebetween a chamber H. In the drawings I show this chamber as being coextensive with the side walls of the water-chamber and with all but a small central portion 65 of its bottom. It is obvious that it may be either less or more extensive than as shown without departing from the scope of the invention. A tip K leads from the generating-chamber through the outer bottom wall F of 70 the water-chamber into the cooling and condensing chamber H, and a tube M leads from the latter chamber to the burner-tip. For convenience and cheapness of construction I prefer to run this tube through the water- 75 chamber C, as shown.

While the width of the chamber H at any part is small, it is nevertheless of very considerable capacity, and the gas passes through it slowly and in a very thin sheet. In passing through this chamber the gas travels over cool surfaces of very considerable area, the wall E being cooled by the water in the chamber C and the wall F being cooled by the surrounding atmosphere. When the lamp is 80 used upon a bicycle, the cooling effect of the atmosphere is very pronounced, as the movement of the bicycle causes a very rapid change of the air, and it consequently carries off a large amount of heat. The gas leaves the 90 chamber H quite cool, and the moisture is practically all condensed out of it and finds its way back into the generating-chamber through the pipe K. The tendency of the flame to lose its luminosity is entirely obviated, and the deposit of solid matter within the tube is so far prevented that it ceases to 95 become an annoyance.

Although in the form of lamp shown the most convenient location for the cooling and 100

condensing chamber is the one selected, it may be found in other forms of lamps advisable to differently dispose it.

The invention is applicable to any form of lamp, and I do not therefore desire to be limited to the location of the gas-chamber between double walls of the water-chamber.

I claim as my invention—

1. In an acetylene-lamp, in combination, a generator, a water-chamber above the generating-chamber, a burner, and a chambered jacket for the water-chamber having its outer wall exposed to the atmosphere, its chamber forming a part of the gas-passage from the generator to the burner and being in communication at its bottom with the generating-chamber, whereby the water of condensation may pass back therefrom into the latter chamber, substantially as and for the purpose described.

2. In an acetylene-lamp, the combination with a generator and burner, of a water-chamber above the generating-chamber and having double walls, spaced apart, its outer wall being exposed to the atmosphere, a tube leading from the generator to the chamber inclosed between the double walls, and a tube leading therefrom to the burner.

3. In an acetylene bicycle-lamp, in combination, a generating-chamber, a water-chamber above the generating-chamber, and a flame-chamber above the water-chamber, such three chambers being vertically alined, the water-chamber having double walls spaced apart to form a gas-cooling chamber whereby the gas is passed about the water-chamber in a thin sheet; connection between the generating-chamber and the cooling-chamber through the bottom of the latter, whereby the water of condensation is drained back to the generating-chamber; and a gas-pipe leading from the cooling-chamber to the flame-chamber.

4. In an acetylene bicycle-lamp, in combination, a generating-chamber, a water-chamber above the generating-chamber and spaced

apart therefrom, and a flame-chamber above the water-chamber, such three chambers being vertically alined, the water-chamber having double walls spaced apart to form a gas-cooling chamber whereby the gas is passed about the water-chamber in a thin sheet; connection between the generating-chamber and the cooling-chamber through the bottom of the latter, whereby the water of condensation is drained back to the generating-chamber; and a gas-pipe leading from the cooling-chamber to the flame-chamber.

5. In an acetylene-lamp, in combination, a water-chamber, a generating-chamber below the water-chamber, connection between the water-chamber and the generating-chamber whereby water is conveyed from the one to the other and its flow is retarded by an excess of gas-pressure, a casing inclosing the water-chamber and forming with the walls thereof a cooling-chamber for gas, such casing being exposed to the atmosphere, connection between the generating-chamber and the cooling-chamber and opening through the bottom of the latter, and a pipe leading from the cooling-chamber.

6. In an acetylene-lamp, in combination, a generator, a water-chamber above the generating-chamber, a burner, and a chambered jacket for the water-chamber, forming a part of the gas-passage from the generator to the burner, and such chamber being without communication with the water-chamber.

7. In an acetylene-lamp, the combination with a generator and burner, of a water-chamber above the generating-chamber and having double walls, spaced apart, a tube leading from the generator to the chamber inclosed between the double walls, and a tube leading therefrom to the burner, there being no communication between the water-chamber and the gas-passage.

JOHN A. MOSHER.
